UNITED STATES PATENT OFFICE.

EDWARD W. SCOTT, OF ATTLEBOROUGH, MASSACHUSETTS, ASSIGNOR TO
THE WATSON & NEWELL COMPANY, OF SAME PLACE.

DESIGN FOR SPOON, &c.

SPECIFICATION forming part of Design No. 25,690, dated June 30, 1896.

Application filed February 25, 1896. Serial No. 580,749. Term of patent 7 years.

To all whom it may concern.

Be it known that I, EDWARD W. SCOTT, a citizen of the United States, residing at Attleborough, in the county of Bristol and State of Massachusetts, have invented and produced a new and original Design for Spoons, Forks, and Similar Articles, of which the following is a full, clear, and exact specification, reference being had to the accompanying drawings, forming a part thereof.

Figure 1 is a plan or obverse view of a spoon, illustrating my new design. Fig. 2 is a similar view of the reverse surface of said spoon and the design thereon.

15 The leading feature of my design is the combination of the unique outline and surface ornamentation of the handle and the shank extending therefrom.

The general outline of the handle A is of 20 an elliptical order, the edge of said handle being irregularly scalloped by raised scroll-work, which borders the edge of the handle and which comprises a part of the surface ornamentation of the same.

25 B B are C-scrolls alternately facing in opposite directions and formed on the obverse surface of the handle adjacent to and bordering on its edge. Clustered within some of said scrolls B and convolving therewith are 30 smaller derivative scrolls, and also comma-like ornamentations I I, which tend to elaborate the decoration of the obverse surface of the handle.

The shank projecting from the handle A 35 and connecting one end of the same with the bowl D tapers slightly to its narrowest point,

which is at an intermediate point about midway between said handle and said bowl.

E E are plain thread-beadings extending along each edge of said shank, the ends of 40 said beading E E adjacent to the bowl of the spoon terminating in C-scrolls e e, which turn inwardly and approach each other. Between said beads E E is arranged a series of beaded projections F, of globular or pearl-like outline, the diameters of said beaded projections F decreasing as they approach the narrowest point in said shank.

The ornamentation of the reverse side of the spoon consists, mainly, in C-scrolls G G, 50 formed on the surface adjacent to the edge of the handle, the alternate scrolls facing in opposite directions, and the plain thread-like beads H H along opposite sides of the shank, the extremities of said beads forming into 55 C-scrolls N N, which approach each other at each end of the shank.

What I claim is—

1. The design for the handle and shank of a spoon, fork or similar article, herein shown 60 and described.

2. In the design for a spoon, fork or similar article, the obverse side of the handle and shank herein shown and described.

3. In the design for a spoon, fork or similar article, the reverse side of the handle and shank herein shown and described.

EDWARD W. SCOTT.
